UNITED STATES PATENT OFFICE.

CHARLES C. TRUAX, OF COLUMBUS, OHIO.

SEPARATOR FOR CORNCOBS AND THE LIKE.

Application filed October 21, 1924. Serial No. 744,963.

This invention relates to a separator, and more particularly to a separator for corn cobs and the like, having mechanical means for separating the shelled corn, and pneumatic means for effecting a treble separation of cobs, husks and dust, and foreign material.

It is an object of my invention to provide means for obtaining cleaned cobs in a condition suitable for immediate grinding.

It is a further object of this invention to provide a complete separator adapted to receive corn cobs just as they come from the sheller, piles or bins, and perform the quadruple separation above described.

It is a further object of this invention to provide simple and efficient pneumatic means for effecting the separation of foreign material, dust and husks, and corn cobs, by a blast of air.

According to my invention, the cobs, which have been previously passed through a sheller, are placed upon a reciprocatory screen or sieve, through which the shelled corn drops into a pocket by itself. The cobs, shucks and all foreign material tail off into my pneumatic separator. Here a powerful suction fan pulls the cobs up over an inverted V-shaped hump or incline, at the same time removing the dust and portions of shucks from the cobs and carrying the latter to a dust collector. The cleaned cobs then drop into a hopper on the far side of the incline. The heavy foreign materials, such as iron, stones, concrete and the like, are not drawn up over the incline by the fan, but fall through an opening at the base of the incline, through which opening the suction fan obtains its supply of air. A treble separation of cobs, dust and shucks, and foreign material is thus effected in the pneumatic separator.

In the drawings, which form a part of this specification,

Figure 1 is a top plan view of my separator;

Figure 2 is a central longitudinal section thereof;

Figure 3 is a vertical section, taken on the line 3—3 of Figure 2; and

Figure 4 is a detail of a shaft and eccentric.

Referring more particularly to the drawings, in which like reference numerals are applied to like parts throughout the several views,

10 designates the frame of my separator, which may be substantially rectangular in shape, and may comprise a plurality of legs or uprights 11, cross bars 12, and longitudinal frame members 13. A screen or sieve 14 is mounted on a suitable rectangular frame 15, the sieve being arranged to discharge into a hopper 16 fastened to the underside of the frame 15. The front and rear ends of the frame 15 are mounted on one leaf of hinges 17 and 18 respectively, rear hinge 18 being shorter than hinge 17, so that the sieve is inclined downwardly and rearwardly. The other leaves of the hinges 17 are secured to intermediate cross bars 12, permitting the screen to move to and fro. The means for reciprocating the screen comprise a cross shaft 19 having an eccentric portion 20 cut therein, and a member 21 secured at one end to the frame 15, and having at the other end a groove and a grooved cap 22, together forming a slot 23 fitting over the eccentric 20. The slot 23 is vertically elongated, as shown clearly in Figure 2, so that the eccentric 20 moves freely therein in a vertical direction, hence a substantially horizontal reciprocating movement is imparted to screen 14 by rotation of shaft 19.

The shaft 19 is mounted at each end in hangers 24 secured to uprights 11, and has pulleys at each end, the purpose of which will be pointed out later. The shaft 19 is, of course, mounted in the plane of frame 15, as shown in Figure 2.

The rear end of screen 14 projects through an opening 25 into an enclosed chamber 26 built on the back portion of frame 10. An incline 27 is placed adjacent the rear end 95 of the screen 14, leaving a space 28 between the base of the incline and a plate or tail board 29, which may be formed of sheet metal, extending from the rear of frame 15. The opening 25 is nearly closed by a sheet 100 of canvas or other flexible material 30.

A back board 31 leads down from the apex of incline 27 to a hopper 32. The hopper 32 is normally closed, and is provided with a door 33 on its front side. This door 105 may be retained in a closed position by a spring hinge 34, or weights might be used for this purpose. A wire or rod 35 connects the door 33 with a swinging arm 36, pivoted on a hinge 37 secured to a lower 110 cross piece 12. A cross shaft 38 is provided with a collar 39 carrying a stud or

projection 40. When shaft 38 is rotated counter-clockwise as shown in Figure 2, projection 40 strikes the arm 36 and moves it outward, causing the door 33 to open. A 5 large pulley is mounted on one end of shaft 38.

A member 41 is placed below back board 31, and forms with the lower portion of the front wall of chamber 26, a funnel-like 10 opening 32. Member 41 also serves as a brace for the inverted V-shaped hump formed by incline 27 and back board 31.

A fan 42 is mounted on a shaft 43 disposed in the upper part of chamber 26. Shaft 43 15 is supported in bearings 44 located in the side walls of chamber 26, and is prevented from endwise displacement by collars 45. A casing 46 surrounds the suction fan 42, openings 47 being provided for ingress of 20 air and an opening 48 for the exhaust. Vertically movable dampers 49 at each side of casing 46 permit partial closing of the openings 47, to regulate the suction of the fan. Pulleys are provided at each end of shaft 43.

25 One of the pulleys on shaft 43 is connected to a suitable source of power (not shown), and the other pulley is coupled by a belt 50 to a pulley on shaft 19. Belt 51 in turn couples the other pulley on shaft 19 with 30 the pulley on shaft 38. As is clearly shown in Fig. 3, the sizes of these various pulleys are so chosen that shafts 19 and 38 will rotate at suitable speeds with respect to shaft 43. Of course, as will be readily understood, 35 gearing might be substituted for the pulleys, and many other changes might be made without affecting the spirit of my invention.

In the operation of my separator, power 40 is applied to cause rotation of shaft 43, which in turn, as above described, rotates shafts 19 and 38. Corn cobs are dumped on the vibrating screen 14 by some suitable means (not shown), such as a conveyor or a 45 hopper, and the shelled corn drops through the openings in screen 14 into hopper 16. A suitable bin (not illustrated) may be placed beneath the hopper 16 to receive the shelled corn. The sieve may have perforations of any size suitable for this purpose, 50 and may be made of wire mesh cloth.

The reciprocatory movement of the screen shakes the tailings down onto the tailboard 29. Here the powerful suction of fan 42 pulls upon the cobs and pulls them up incline 27, at the same time stripping the 55 remnants of husks from them. These husks, together with all dust and dirt, pass through the fan and are discharged from opening 48 into a suitable dust collector (not shown), 60 from which the shucks may be removed for baling.

The bin or hopper 32 is closed tightly by door 33, and opening 25 is kept closed by the canvas strip 30 and the material on the 65 screen, so that the fan draws substantially

all of its air through the channel formed by openings 42 and 28. The corn cobs are not held in suspension by the fan, but are merely pulled or rolled up the incline 27, and then allowed to drop down into bin 32. They are discharged from this bin at periodic intervals by the operation of cam 40, arm 36 and wire 35, which open the door 33 once for each revolution of shaft 38, as above described.

75 The opening 28 is too small to permit the corn cobs to drop therethrough, but the heavy foreign materials, such as iron, stones, concrete and the like, are not lifted by the fan and drop off the tailboard 29 through 80 the openings 28 and 42 into a suitable receptacle (not shown) which may be placed to receive them.

A complete separation of shelled corn, foreign material, husks and dust, and cleaned 85 cobs, is thus effected by my apparatus.

The member 27 may be made adjustable to vary the incline up which the cobs move as described. The means for this purpose may comprise a hinge 52 mounted at the apex 90 of members 27 and 31, and an adjusting screw 53 threaded through a bracket secured to member 31 and held in a swivel socket attached to member 27. The member 27 is thus positively held in the desired position 95 by the adjusting screw.

Many changes might be made in my invention within the spirit thereof, and I do not wish to be limited except by the prior art and the scope of the appended claims.

Having thus described my invention what I claim as new and desire to be secured by Letters Patent is:

1. An apparatus for separating shelled corn, husks and like particles from corn cobs, comprising in combination, a vibratory sieve for separating the shelled corn, a chamber arranged at the tail end of said sieve and having an opening through which the remaining material passes from said sieve into the chamber, an upwardly directed incline arranged in said chamber adjacent said opening and the tail end of said sieve so that the cobs are required to pass upwardly over the same upon entering the chamber, a settling chamber into which the upper end of the incline delivers, and means for creating a forced draft up said incline to lift the cobs over the same to permit them to drop into the settling chamber and to simultaneously draw off the husks and like particles.

2. An apparatus for separating shelled corn, husks and like particles from corn cobs, comprising in combination, a vibratory sieve for separating the shelled corn, a chamber arranged at the tail end of said sieve and having an opening through which the remaining material passes from said sieve into the chamber, an upwardly di- 130

rected incline arranged in said chamber adjacent said opening and above the tail end of said sieve so that the cobs are required to pass upwardly over the same upon entering the chamber, a settling chamber receiving from the upper end of said incline and a suction fan arranged in the upper portion of said chamber and serving to create a forced draft up said incline to lift the cobs over the same and permit them to drop into said settling chamber and simultaneously draw off the husks and like particles.

3. The combination as claimed in claim 1, in which the settling chamber for receiving the cobs after the same pass over said incline, is provided with a normally closed door, and automatic means for periodically opening said door, whereby the greater part of the draft is preserved, in delivering the settled cobs.

4. An apparatus for separating shelled corn, like particles and husks from corn cobs, comprising in combination, a vibratory sieve for separating the shelled corn, a chamber arranged at the tail end of said sieve and having an opening through which the material passes from said sieve into the chamber, an inverted V-shaped hump in said chamber, one side of said hump terminating adjacent said opening and positioned to cause the cobs to travel up the same after they enter said chamber, the other side of said hump delivering to a settling chamber and means for creating a forced draft through said opening and up the side of said hump to lift the corn cobs over the hump

to fall into the settling chamber and to simultaneously draw off the husks and like particles.

5. The combination as claimed in claim 4, in which said side of the hump adjacent said opening is adjustable to vary its angle with the horizontal.

6. The combination as claimed in claim 4, in which the settling chamber for receiving the cobs after they pass over said hump, is provided with a normally closed door adjacent the bottom thereof and automatic means for periodically opening said door whereby the interruption of the draft is reduced to a minimum in delivering the settled cobs.

7. An apparatus for separating shelled corn, husks and like particles from corn cobs, comprising in combination, a vibratory sieve for separating the shelled corn, a chamber arranged at the tail end of said sieve and having an opening through which the remaining material passes from said sieve into the chamber, said opening being restricted to minimize the admission of air, and an upwardly directed incline arranged in said chamber adjacent said opening and so positioned that the cobs are required to pass upwardly over the same upon entering the chamber, and means for creating a forced draft up said incline to lift the cobs over the same and to simultaneously draw off the husks and like particles.

In testimony whereof I hereunto affix my signature.

CHARLES C. TRUAX.
